SCRAPER LOADER APPARATUS

Timothy F. McCarthy, Indiana, Pa.

Application February 15, 1945, Serial No. 577,971

9 Claims. (Cl. 37—115)

1

This invention relates to improvements in scraper loader apparatus particularly adapted to handle loose material in mines underground, and has as its principal objects to provide an improved form of head frame adapted to guide a scoop or scraper to pick up loose material from the working face of a mine where the bottom is irregular or rolling.

Another object of my invention is to provide a novel and efficient form of extensible and flexible head frame for a scraper, arranged to carry the scraper over rolls in the mine bottom and to guide the scraper to load out the material over the top of the roll and then by movement of the head frame to guide the scraper to load out the roll and the loose material on the ground, after the roll has been shot.

A more specific object of my invention is to provide a movable head frame for a scraper loader apparatus including a guide frame extending along the working face of a mine and along opposite ribs thereof, and having a bottom pan extending outwardly therefrom, which is adapted to have the scraper movable therealong, to form a flexible ramp or roadway for the scraper, to carry the scraper over an uneven mine bottom.

An application Serial No. 568,119, filed by me on December 14, 1944, shows a form of extensible head frame somewhat similar to that of my present invention. The head frame of my present invention, however, differs from that shown in my prior application in that it is provided with an outwardly extending pan forming a supporting ramp or roadway for the scraper, to carry the scraper over an uneven mine bottom, and is also transversely hinged, to permit the head frame to more readily conform to the mine bottom.

My invention may be more clearly understood with reference to the accompanying drawings wherein:

Figure 1 is a diagrammatic plan view of a material handling apparatus constructed in accordance with my invention, showing the apparatus in position for loading from a mine room;

Figure 2 is a diagrammatic longitudinal sectional view taken substantially along line 2—2 of Figure 1;

Figure 3 is an enlarged fragmentary detail plan view of the loading apparatus, with certain parts broken away and certain other parts shown in substantially horizontal section;

Figure 4 is a transverse sectional view taken substantially along line 4—4 of Figure 3, showing the scraper in transverse section and in a differ-

2

ent position along the head frame than in Figure 3;

Figure 5 is a fragmentary detail view showing certain details of one of the supporting jacks 5 for the head frame and showing the construction of the hinged portion of the head frame in substantially longitudinal section;

Figure 6 is an enlarged detail plan view with certain parts broken away and certain other parts shown in horizontal section in order to show certain details of the transverse hinged construction of the head frame;

Figure 7 is a fragmentary detail sectional view taken substantially along line 7—7 of Figure 3;

Figure 8 is a fragmentary detail sectional view taken substantially along line 8—8 of Figure 3;

Figure 9 is a fragmentary detail transverse sectional view taken substantially along line 9—9 of Figure 3; and

Figure 10 is a fragmentary detail sectional view taken substantially along line 10—10 of Figure 3.

In the embodiment of my invention illustrated in the drawings, a head frame 10 is shown as being positioned adjacent a working face of a mine to form a reaction member for and to guide a scraper 11 into and across the working face, to pick up mined material, such as coal, therefrom.

The scraper 11 is herein shown as being a hinged type of scraper having an inner side wall 12 substantially conforming to the curved form of the head frame 10, and having an outwardly and forwardly curved outer side wall 13 pivotally connected to the rear end of said inner side wall. Said side walls are connected together at their forward ends by means of a pair of toggle links 14, 14 pivotally connected to the forward inner sides of said side walls, adjacent the lower ends thereof. A head rope 15 is provided to pull said scraper in a forward direction. Said head rope is connected to a connecting member 16 which is slidably connected to said toggle links for movement therealong as the angle of said head rope with respect to said scraper changes, to cause said head rope to hold said scraper in engagement with said head frame. Said scraper is of a form clearly shown and described in an application Serial No. 573,505, filed by me on January 19, 1945, so need not herein be described in detail.

A tail rope 18 is connected to the rear end of the outer side wall 13 of said scraper and serves to move said scraper in a reverse direction, to position it to obtain a new bite on the material it is desired to load and to form a reaction means for the scraper as it travels about said head frame, and to aid in holding said scraper in the

proper relation with respect to said head frame during travel of said scraper thereabout.

The head frame 10 includes a guide frame 19 extending along one rib of the working place, a guide frame 20 extending along the opposite rib of the working place, and a forward guide rail 21 adjustably and detachably connected to said guide frames 19 and 20, to form a means for guiding the scraper along the working face of the mine from one side frame member to the other, for picking up loose material from the working face while reacting against said guide rail 21. Said guide rail 21 is detachably connected to the guide frames 19 and 20, to permit the space between said frames to be opened to receive and store a cutting machine (not shown) during the loading operation, and may be of various lengths of working places. It may also be sectional, if desired, as in my application Serial No. 568,119.

The guide frames 19 and 20 are of the same construction except the guide frame 19 is arranged to extend along the left rib of the working place and the guide frame 20 is arranged to extend along the right rib of the working place, so one of said guide frames only will be described in detail herein and the same part numbers will be applied to similar parts of each of said guide frames.

The guide frame 19 has a longitudinally extending guide rail 23 spaced above the ground, and herein shown as being substantially parallel to the left-hand rib of the working place during the loading operation. Said guide rail is herein shown as being constructed from a channel opening towards the ground and has inwardly curved forward and rear ends, and is adapted to be engaged by the inner side wall 12 of the scraper 11 and form a guide means for said scraper 11 as it moves towards or away from the working face. A plurality of support members 24, 24 form a support for said guide rail and space it above the ground. Said support members will hereinafter be more clearly described as this specification proceeds, and rest on and are secured to a bottom pan 25, extending laterally from and along said guide rail and forming a ramp or roadway along which the scraper 11 travels.

A longitudinally extending beam 26 is secured to the inner end of the inwardly curved rear end of the guide rail 23, and extends forwardly therefrom in substantially parallel relation with respect to the rectilinear portion of said guide rail. Said beam is herein shown as being tubular, and is connected at its forward end to a transversely extending member 27 connected at its end opposite said beam to said guide rail 23. A piston rod 29, extensible from a longitudinally extending cylinder 30, is connected to said member 27 and serves to advance or retractably move said guide frame with respect to the working face. Said cylinder extends through and is secured to a bracket 31 extending outwardly from a jack 33, which is adapted to be interposed between the mine roof and the mine bottom, to hold said guide frame 19 in position on the ground. Said cylinder is supported adjacent its rear or head end on a bracket 32 slidably mounted on the beam 26. Thus when the jack 33 is held in a stationary position, between the mine roof and the mine bottom, the admission of fluid under pressure to the head end of the cylinder 30 will advance said guide frame towards the working face. In a like manner, the

admission of fluid under pressure to the piston rod end of said cylinder will retractably move said head frame with respect to the working face.

The jack 33 is herein shown as being a fluid pressure jack and includes an upright cylinder 34 having a piston 35 movable therein. A piston rod 36 having a roof engaging member 37 secured to its upper end extends from said piston. A bifurcated member 39 depends from the lower end of said cylinder and has a floor engaging shoe 40 transversely pivoted thereto.

The bracket 31 is slidably mounted on the cylinder 34 for vertical adjustment with respect thereto. Said bracket has an outwardly extending and upwardly projecting support portion 43, which extends upwardly along the inner flange of the channel of the guide rail 23. Said upwardly projecting support portion forms an adjustable support for said guide rail on said bracket and serves to lift said guide rail and the bottom pan 25 above the ground, upon vertical movement of said bracket along said cylinder.

The bracket 31 is vertically moved along the cylinder 34, or is held in fixed relation with respect thereto by means of a cylinder 44 having a piston rod 45 extensible from its lower end. Said cylinder is mounted in a rearwardly projecting part 46 of said bracket 31, and said piston rod is mounted at its lower end in a bracket 47 projecting rearwardly from the member 39 (see Figure 5). When fluid under pressure is admitted to the head end of said cylinder 44, said bracket 31 will be vertically moved along the cylinder 34 in an obvious manner.

The beam 26 extends through a yoke 50, mounted at its ends in the outer end of the bracket 31, and is slidably supported in said yoke on a roller 51. Said roller has a convex face forming a support for said beam, and is rotatably mounted on a transversely extending cap screw 52, which serves to secure the lower end of said yoke to said bracket (see Figure 4).

The rear part of said guide frame is held in position by means of a fluid jack 54, similar to the jack 33 but having no elevating cylinder associated therewith. Since said jack 54 is like the jack 33, it need not herein be shown or described in detail.

The support members 24, 24, for the guide rail 23, each have an upwardly projecting support portion 55, which extends within the channel of said guide rail and abuts the inside of the outer web of the channel of said guide rail. Said support portion is secured to said guide rail, as by welding, to support said guide rail on said bottom pan in vertically spaced relation with respect thereto. Said support members each have a lower inwardly extending recessed portion 59 having a sheave 60 mounted therein on a vertical pin 61. Said sheave is adapted to form an anti-friction guide for the head and tail ropes of the scraper, and the advance outer lower portion of the base of said support member extends beyond the flange of said roller and is inclined upwardly from said bottom plate at an angle herein shown as being in alignment with the angle of the flange of said sheave, to deflect the head or tail ropes for the scraper into the groove of said sheave, when slack is taken up on said ropes. The advance face of the support portion 55 of said support member is inclined inwardly from the outer side of the guide rail 23 so as to deflect the head or tail ropes into the groove of said sheave.

The forward portion of the guide frame 19 is

transversely pivoted to permit said guide frame to more readily follow an uneven mine bottom. Said forward portion of said guide frame includes an inwardly curved guide rail 63, forming a forward extension of the guide rail 23. Said guide rail 23 has a depending forwardly projecting hinge member 64 which interleaves a depending rearwardly projecting hinge member 65 of the guide rail 63 and which is pivotally connected thereto by a pivotal pin 66. A tube 69 forms a forward extension of the beam 26 and is pivotally connected to the forward end of said beam by means of a pivotal pin 70 extending through interleaving hinge members 71, 72 projecting forwardly and rearwardly from said beam 26 and tube 69, respectively. The pivotal axis of said tube 69 is coaxial with the pivotal axis of the inwardly curved guide rail 63. Said tube 69 intersects said guide rail at its forward end and is suitably secured thereto (see Figure 3).

The inner end of the guide rail 63 is curved inwardly at a sharper angle than the main portion thereof and is supported just before this sharply curved inner end on a support member 67 somewhat similar to the support members 24, 24. Said guide rail is also engaged and detachably supported by an outwardly extending and upwardly projecting end portion of a support bracket 73 on a headed pin 73a extending inwardly from said end portion of said support bracket. Said pin is adapted to be engaged by a slotted portion of the inner flange of said guide rail 63 and its head is adapted to engage the outside of the flange of said guide rail to retain said guide rail in position on said bracket. Said bracket is slidably mounted on a vertical cylinder 74 of a fluid jack 75, much like the bracket 31 is mounted on the cylinder 34 of the jack 33 (see Figure 9).

The jack 75 is similar to the jack 33 so need not herein be shown or described in detail. A cylinder 76 having a piston rod 79 extensible from its lower end depends from a rearwardly extending upper projection 77 of the bracket 73. The lower end of said piston rod engages a support 80 projecting rearwardly from the lower end of said cylinder 74. The admission of fluid under pressure to the head end of said cylinder will thus elevate said bracket and the forward portion of the head frame 10.

A curved bottom pan 81 extends outwardly from and conforms to the curve of the guide rail 63. A hinge member 82 is secured to the bottom of said pan 81 and interleaves a hinge member 83 mounted on the forward end of the bottom pan 25. A pivotal pin 84 connects the interleaving portions of said hinge members together. The advance end of said bottom pan 81 overlaps a bottom plate 85, secured to the underside of a bottom pan 86, which extends outwardly from the guide rail 21 and is adapted to support the scraper 11 during movement therealong. A relatively loose connection is provided between said pan 81 and said plate 85, to permit movement of one pan with respect to the other and to permit the bottom pan 81 to move about the axis of the hinge pin 84, in substantially parallel relation with respect to the guide rail 63. Said connection includes a bearing member 87 depending from said bottom pan 81 and extending through an elongated arcuate slot 88 formed in said bottom plate 85. A plate 89 is secured to the bottom of the bearing member 87, to hold said pan 81 and plate 85 in connected relation with respect to each other. Enough clearance is provided be-

tween said plate and the bottom of the plate 85 to provide a sloppy joint.

The bottom pan 86 extends along the guide rail 21 and forms a continuation of the pan 81. The end of said pan 86 opposite from said pan 81 overlaps a plate 90, secured to the bottom of the inner end of a curved bottom pan 91, which is similar to the pan 81. A loose pin and slot connection similar to the connection between the pans 81 and 86, and indicated generally by reference character 92, is provided between said pan 86 and plate 90.

The bottom pan 81 and plate 85 are provided with vertically aligned elongated curved slotted portions 93, 94, respectively, spaced inwardly from the slot 88, through which extends the lower end of a lug 95 depending from the support member 67 for the inner end of the guide rail 63. A retaining plate 96 is secured to the underside of said lug to loosely connect said pan and plates to the underside of said support member, so said pan and plates may have limited freedom of movement with respect to said support member and will move vertically with said support member upon vertical movement thereof.

The right-hand end of the bottom pan 86 is slidably connected with the underside of the right-hand support member 67, to move vertically with said support member upon the admission of fluid under pressure to the cylinder 76 associated with the right-hand jack 75, by means of a loose pin and slot connection (not shown) which is similar to the pin and slot connection connecting the pan 81 and plate 85 to the left-hand support member 67, so need not herein be shown or described in detail.

A support member 97 similar to the support member 67 is interposed between the upper side of the bottom pan 81 and the underside of the inwardly curved guide rail 63. Said support member is secured to the underside of said guide rail as by welding, and is slidably mounted on the upper side of said curved pan 81, to allow for relative movement between said curved pan and guide rail upon movement of said pan and guide rail about their respective hinged connections.

The guide rail 21 is formed from a channel, the flanges of which extend upwardly, and has curved outer ends substantially conforming to the curve of the curved guide rail 63. The left-hand end of said guide rail 21 is detachably and slidably connected to the upper side of said curved guide rail 63, to permit independent movement of the guide frame 19 with respect to the guide frame 20, and to provide an uninterrupted guide for the scraper when said guide frames are in various positions of adjustment with respect to each other. As herein shown, a block 100 is mounted in the space between the flanges of said guide rail and is provided with an elongated curved slot 101 conforming to the form of the slotted portions 93 and 94 of the bottom pan 81 and the plate 85. A pin 103, secured to the guide rail 63 adjacent the support member 67 and projecting upwardly therefrom, is adapted to extend through said curved slot, to form a slideable guide for said guide rail 21, and also to permit longitudinally slideable and pivotal movement of said guide rail 21 with respect to said guide rail 63, so the curved advance portion of said guide rail 21 may form a continuation of the curved forward end of said guide rail 63, in all positions of said guide rails with respect to each other. The right-hand end of said guide rail 21

is slidably and pivotally connected to the curved inner portion of the right-hand guide rail 63 by means of a pin and slot connection indicated generally by reference character 104.

In operation the apparatus is set up in the working place much like the apparatus shown and described in my application Serial No. 568,119. The guide frames 19 and 20 may be independently advanced during the loading operation, as described in my prior application, to enable the entire working face to be completely loaded out by the scraper 11. Where a roll is encountered on the bottom, the head frame may be advanced by the cylinders 33, 30 until the loading pan 86 is as close as possible to said roll. The jacks 33, 33 and 75, 75 being interposed between the mine roof and the mine bottom to hold the head frame in position, fluid under pressure may be admitted to the cylinders 44, 44 and 76, 76, if the roll extends entirely across the working place, to incline the pans 25, 25 upwardly from their rear ends and to elevate the bottom pans 81 and 86 so their bottoms are just above the top of the roll. Timbers may then be placed under said pans to hold them in an elevated position, and fluid pressure may then be released from the cylinders 76, 76 to permit the pans 81 and 86 to rest on said timbers. The jacks 75, 75 may then be released from the mine roof. The jacks 33, 33 being in engagement with the mine roof and fluid pressure being held in the cylinders 44, 44 to hold the guide frame 19 in an inclined position, the entire head frame may be advanced by the admission of fluid under pressure to the head ends of the cylinders 30, 30, to advance said bottom pans over the top of the roll and permit them to rest thereon. If desired, loose coal may be shoveled under said bottom pans, or timbers or mine ties may be placed thereunder, to form a temporary support therefor. The working face may then be shot down onto the loading pans 81, 86 and 91. The scraper 11 may then be moved along said head frame on said bottom pans, to load out the loose material up to the level of said pans. When this loose material has been loaded out, the jacks 75, 75 and 54, 54 may be released from the mine roof and the head frame 10 may be retractably moved, by admitting fluid under pressure to the piston rod ends of the cylinders 30, 30 and releasing it from the head ends thereof, until the bottom pans 81 and 86 have been moved off the roll on the bottom. The roll may then be shot down and the head frame may again be advanced by the admission of fluid under pressure to the head ends of the cylinders 30, 30 and may be held in position by the jacks 75, 75 and 54, 54, to permit the scraper 11 to load out the roll. The head frame may then be further advanced to permit the scraper to load out the loose material in advance of the roll which was left when the bottom pans 81 and 86 were in an elevated position on top of the roll.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. In a head frame for guiding a scraper to pick up loose material from the working face of

a mine, a guide frame adapted to extend along one rib of the working place, a bottom pan extending outwardly from said guide frame and forming a supporting roadway for the scraper, to carry said scraper over an uneven mine bottom, a stationary jack adapted to be interposed between the ground and the mine roof for holding said guide frame in position during loading, and means mounted on said jack for elevating said guide frame and bottom pan to place said bottom pan on top of a roll on the mine bottom, to guide the scraper to move in a plane disposed above said roll and load out material above said roll.

2. In a head frame for guiding a scraper to pick up loose material from the working face of a mine, a guide frame adapted to extend along one rib of the working place, a bottom pan extending outwardly from said guide frame and forming a supporting roadway for said scraper, to carry said scraper over an uneven mine bottom, said guide frame and bottom pan being transversely pivoted to permit said guide frame to conform to an uneven mine bottom, a stationary jack for holding said guide frame in position during the loading operation, a movable jack for holding the forward end of said guide frame in position, and means mounted on said jacks and independently operable to elevate the forward end of said guide frame and hold it in an elevated position to permit the forward end of said guide frame to extend along the top of a roll on the mine bottom, to support the scraper for loading from the top of said roll.

3. In a head frame for guiding a scraper to pick up loose material from the working face of a mine, a guide frame adapted to extend along one rib of the working place, a bottom pan extending outwardly from said guide frame and forming a supporting roadway for said scraper, to carry said scraper over an uneven mine bottom, a stationary jack adapted to be interposed between the ground and the mine roof for holding said guide frame in position during loading, transversely pivoted connections in said guide frame and bottom pan adjacent the forward ends thereof, to permit said guide frame to conform to an uneven mine bottom, a stationary jack for holding said guide frame in position during the loading operation, means connected with said stationary jack for positively moving said guide frame with respect to said jack along the ground, a movable jack connected with the forward end of said guide frame for holding the forward end of said guide frame in position during loading, and a fluid cylinder and piston mounted on each of said jacks, adapted to elevate said guide frame and position it to conform to an uneven mine bottom so it may form a supporting roadway for the scraper, to carry said scraper over an uneven mine bottom.

4. In a head frame for guiding a scraper to pick up loose material from the working face of a mine, a guide frame extending along each rib of the working place, means adjustably connecting said guide frames together and permitting independent advancing movement of one guide frame with respect to the other including a transverse guide rail adapted to extend along the working face, and a separate bottom pan extending outwardly from each of said guide frames and from said guide rail and forming a supporting roadway to carry the scraper over irregularities on the mine bottom during travel of

said scraper up to, along, and away from the working face.

5. In a head frame for guiding a scraper to pick up loose material from the working face of a mine, a guide frame extending along each rib of the working place, means adjustably connecting said guide frames together including a transverse guide rail adapted to extend along the working face, and a separate bottom pan extending outwardly from each of said guide frames and from said guide rail and forming a supporting roadway to carry the scraper over irregularities on the mine bottom during travel of said scraper up to, along, and away from the working face, and transverse pivoted connections in said guide frames and said bottom pans which extend therealong, to permit said guide rail and said bottom pan extending therealong to conform to an uneven mine bottom and to be placed on top of irregularities thereon.

6. In a head frame for guiding a scraper to pick up loose material from the working face of a mine, a guide frame extending along each rib of the working place, means adjustably connecting said guide frames together including a transverse guide rail adapted to extend along the working face, and a separate bottom pan extending outwardly from each of said guide frames, another bottom pan extending outwardly from said guide rail, said bottom pans forming a supporting roadway to carry the scraper over irregularities on the mine bottom during travel of said scraper up to, along, and away from the working face, a separate stationary holding jack for holding each of said guide frames in position, said jacks being adapted to be interposed between the ground and the mine roof, and means mounted on said jacks for elevating the forward portions of said guide frames to place said bottom pan, which extends along said guide rail and the working face, into position to be placed on top of a roll on the mine bottom, to support said scraper during movement over said roll.

7. In a head frame for guiding a scraper to pick up loose material from the working face of a mine, a guide frame extending along each rib of the working place, means adjustably connecting said guide frames together including a transverse guide rail adapted to extend along the working face, and a separate bottom pan extending outwardly from each of said guide frames and from said guide rail and forming a supporting roadway to carry said scraper over irregularities on the mine bottom during travel of said scraper up to, along, and away from the working face, a separate stationary holding jack adapted to be interposed between the ground and the mine roof for holding each of said guide frames in position, a fluid pressure cylinder and piston mounted on each of said jacks and having operative connection with said guide frames for moving said guide frames along the ground independently of each other, and other fluid pressure cylinders and pistons mounted on said jacks and having operative connection with said guide frames for elevating the advance ends of said guide frames, and for holding said guide frames in an elevated position to conform to an uneven mine bottom and to position said bottom pan which extends along the working face on top of a roll on the mine bottom.

8. In a head frame for guiding a scraper to pick up loose material from the working face of

a mine, a guide frame extending along each rib of the working place, means adjustably connecting said guide frames together including a transverse guide rail adapted to extend along the working face, and a separate bottom pan extending outwardly from each of said guide frames and from said guide rail and forming a supporting roadway to carry said scraper over irregularities on the mine bottom during travel of said scraper up to, along and away from the working face, and transverse pivoted connections in said guide frames and said bottom pans which extend therealong, to permit said guide rail and its associated bottom pan to conform to an uneven mine bottom, a separate stationary holding jack adapted to be interposed between the mine roof and the mine floor for holding each of said guide frames in position, support means mounted on said jacks for vertical movement therealong and supporting connections between said support means and said guide frames, elevating means operatively connected with said support means for elevating the forward ends of said guide frames, a separate movable holding jack for the forward portions of the pivoted portions of each of said guide frames, for holding said pivoted portions of said guide frames from movement with respect to the ground during the loading operation, and means mounted on said jacks for vertical movement therealong for elevating the pivoted portions of said guide frames and for lifting said guide rail and its associated bottom pan above the ground about said pivoted connections.

20 9. In a head frame for guiding a scraper to pick up loose material from the working face of a mine, a guide frame extending along each rib of the working place, means adjustably connecting said guide frames together including a transverse guide rail adapted to extend along the working face, and a separate bottom pan extending outwardly from each of said guide frames and from said guide rail and forming a supporting roadway to carry said scraper over irregularities on the mine bottom during travel of said scraper up to, along and away from the working face, transverse pivoted connections in said guide frames and said bottom pans which extend therealong, to permit said guide rail and its associated bottom pan to conform to an uneven mine bottom, a separate stationary holding jack adapted to be interposed between the mine roof and the mine floor for holding each of said guide frames in position, support means mounted on said jacks for vertical movement therealong and supporting connections between said support means and said guide frames, elevating means operatively connected with said support means for elevating the forward ends of said guide frames, a separate movable holding jack for the forward portions of the pivoted portions of each of said guide frames, for holding said pivoted portions of said guide frames from movement with respect to the ground during the loading operation, and means mounted on said jacks for vertical movement therealong for elevating the pivoted portions of said guide frames and for lifting said guide rail and its associated bottom pan above the ground about said pivoted connections.

25 10. In a head frame for guiding a scraper to pick up loose material from the working face of a mine, a guide frame extending along each rib of the working place, means adjustably connecting said guide frames together including a transverse guide rail adapted to extend along the working face, and a separate bottom pan extending outwardly from each of said guide frames and from said guide rail and forming a supporting roadway to carry said scraper over irregularities on the mine bottom during travel of said scraper up to, along and away from the working face, transverse pivoted connections in said guide frames and said bottom pans which extend therealong, to permit said guide rail and its associated bottom pan to conform to an uneven mine bottom, a separate stationary holding jack adapted to be interposed between the mine roof and the mine floor for holding each of said guide frames in position, a fluid pressure cylinder and piston on each of said stationary jacks having operative connection with said guide frames for rectilinearly moving said guide frames along the ground independently of each other, other fluid pressure cylinders and pistons on said jacks and having operative connection with said guide frames for elevating the advance ends of said guide frames and for holding said guide frames in an elevated position, a separate movable holding jack for the forward portions of the pivoted portions of said guide frames for holding said pivoted portions of said guide frames from movement about the ground, and fluid pressure means on said jacks for elevating the pivoted portions of said guide frames and for lifting said guide rail and its associated bottom pan above the ground into position to be placed on top of a roll on the mine bottom.
